UNITED STATES PATENT OFFICE.

FRANK W. MANSFIELD, OF CANTON, MASSACHUSETTS.

STOP MOTION FOR BRAIDING MACHINES.

Application filed May 27, 1922. Serial No. 564,058.

To all whom it may concern:

Be it known that I, FRANK W. MANSFIELD, a citizen of the United States, and resident of Canton, county of Norfolk, State 5 of Massachusetts, have invented an Improvement in Stop Motions for Braiding Machines, of which the following description, in connection with the accompanying drawing, is a specification, like characters 10 on the drawing representing like parts.

This invention relates to braiding machines and particularly to stop motions for braiding machines and has for its object to provide a novel stop motion which is constructed to automatically stop the machine whenever an imperfection is formed in the braided product delivered from the machine which causes an increase in the size 15 of the product.

20 The invention is useful in connection with any braiding machines where it is desired to produce a braided product which is free from knots, bunches or enlargements, but it is especially useful in connection with 25 braiding machines that are adapted to braid fish lines or other similar cord because it provides for stopping the braiding machine at once in case a knot or other bunch is braided into the product in such a way as 30 to cause a bunch or enlargement therein.

The invention consists of a gauging eye which is situated just above the braiding point and through which the product passes, said eye having a diameter of a size 35 to permit the product to freely pass so long as it is of the required size but which will prevent the passage of a bunch or an enlargement in the product. This gauging eye is so connected with the stop mechanism 40 that whenever a bunch or enlargement engages the eye the stop motion will be operated to stop the machine automatically.

In order to give an understanding of the invention I have illustrated in the drawings 45 a selected embodiment thereof which will now be described after which the novel features will be pointed out in the appended claims.

Fig. 1 of the drawings is a side view of a 50 braiding machine embodying my invention with most of the braiding carriers omitted.

Fig. 2 is a horizontal sectional view taken just above the plate 2.

Fig. 3 is a side view of the driving clutch.

Fig. 4 is a view of the gauging eye. 55

The braiding machine herein shown is of the well-known construction and comprises a base 1 supporting a plate 2 in which is formed the raceways 3 in which the spindles 4 of the braiding carriers 5 operate, 60 each carrier having a bobbin 6 thereon. These carriers are moved through the raceways by means of the usual gears 7 that are situated below the plate 2 and said gears 7 are driven from a driving gear 8 which is fast on a vertical shaft 9. The driving gear 8 is in turn driven from a belt pulley 10 that is loose on said shaft, said belt pulley being operated from a driving belt 13 provided with a clutch member 11 adapted 65 to be clutched to a clutch member 12 rigid with the driving gear 8. The driving pulley 10 is slideable longitudinally of the shaft 9 and when it is in its elevated position shown in full lines Fig. 3 it will be clutched 70 to the gear 8 and shaft 9 thereby operating the machine, but when it is lowered into the dotted line position it is disengaged from the driving gear 8 and the machine will 75 come to rest. 80

The pulley 10 is raised into its elevated position by means of a lever 14 pivoted to the frame at 15 and situated beneath the pulley, said lever thus constituting a support for the driving pulley. This lever has a latch 16 pivoted thereto which is adapted to engage an arm 17 on a swinging knock-off member 18 that is situated above the plate 2 and is pivoted thereto at 19, said knock-off member being normally held in 85 the position shown in Fig. 2 by means of a spring 20. This knock-off member is adapted to be engaged by the tension weight 21 on any bobbin carrier when it falls due to breakage of the corresponding thread, the 90 engagement of the fallen tension weight with the knock-off member 18 swinging the latter into the dotted line position Fig. 2 thereby releasing the finger 17 from the latch 16 and allowing the lever 14 and pulley 10 to drop into the dotted line position 95 Fig. 3 thus disconnecting the driving ele- 100

ment from the gear 8 and stopping the machine.

The parts thus far described are or may be all as usual in braiding machines and 5 form no part of the present invention, and in the operation of the machine the braiding carriers are carried around in the races 3 thereby to braid together the threads 22 from the various bobbins to form the cord 10 or other finished product 23. This cord may be either a round cord or a flat cord depending on the character of the raceways 3.

The present invention relates to a novel device for stopping the machine automatically in case the cord or other braided product 23 is formed with a bunch or knot or other enlarged spot. This is accomplished by providing a gauging eye 24 which is situated just above the braiding point 25 and 15 which is of a size to allow the braided product 23 to pass freely therethrough provided said product does not exceed its proper or predetermined diameter. If the braided product is a round cord or a line such as a 20 fish line, then the hole through the part 24 will be round and will have a diameter just sufficient to permit the cord 23 to pass freely therethrough. This gauging eye is shown as carried by the end of a lever 26 pivoted 25 to the frame as shown at 27. This arm 26 is normally acted upon by a spring which holds it in the horizontal position shown but if for any reason, a knot or bunch is 30 formed in the braided product 23, as indicated by dotted lines 28, the engagement of this knot or bunch with the gauging eye 24 will swing the lever 26 upwardly into the dotted line position.

Means are provided whereby such swinging 40 movement of the lever 26 will operate to release the latch 16 from the knock-off member 18 thus allowing the driving pulley 10 to be automatically disconnected from the driving gear 8.

The formation of the bunch or knot 28 may result from various causes, such for instance as a knot in one of the threads 22 or because some lint or thread end or some other foreign object gets caught on one of 50 the threads 22 or becomes braided into the cord.

The means herein shown for releasing the latch 16 by the swinging movement of the lever 26 comprises a rod 29 which is pivotally connected at its upper end to the end of the lever 26, as shown at 30 and at its lower end is connected to a dog 31 that is 55 slidably vertically on a pin 32 carried by the knock-off member 18. This dog 31 has an arm 33 provided with a shoulder 34.

56 is a spring secured at one end to the frame and at the other end to the rod 29, said spring normally holding the parts in 60 the position shown in Fig. 1. The shaft 9 has a pin or projection 35 extending radially.

therefrom and situated so that when the parts are in full line position Fig. 1 the pin will be below the arm 33 of the dog and, therefore, said pin will not engage the dog 70 as the shaft rotates.

Whenever the lever 26 is moved into the dotted line position by reason of the formation of a bunch or knot 28 in the cord 23, such movement of the lever 26 operates through the rod 29 to lower the dog 31 thereby bringing the shoulder 34 into the path of movement of the pin 35. The shaft 9 is rotating in the direction of the arrow Fig. 2 and when the dog has been thus lowered the pin 35 engages the shoulder 34 and operates through the dog to swing the knock-off member 18 into its dotted line position thus releasing the latch 16 and bringing the machine to rest.

After the knot 28 has been removed and before the machine is started again the lever 26 and dog 31 will be returned to the full line position shown in Fig. 1.

It is desirable that the gauging eye 24 should be situated close to the braiding point 25 and as this point varies in a vertical direction depending on the character of the yarn being braided, I have provided means for adjusting the lever 26 vertically. This is accomplished by pivoting said lever on a supporting member 36 which in turn is vertically adjustable on a bracket arm 37 secured to or forming part of the frame, the member 36 being retained in vertical adjustable position by a clamping bolt 38. 95

The connection 30 between the rod and member 36 is also preferably an adjustable one so as to permit of this desirable vertical adjustment.

While I have illustrated herein a selected 105 embodiment of my invention I do not wish to be limited to the constructional features shown.

I claim:

1. In a braiding machine, the combination with braiding mechanism for forming a braided product having a predetermined transverse dimension, of a driving shaft for operating the machine, said shaft having a projection, a driving pulley slidably mounted on the shaft and adapted by its sliding movement to be clutched to or unclutched from the shaft, a latch for holding the pulley in clutched relation to the shaft, a knock-off lever to retain the latch in its operative position, a dog carried by the knock-off lever and normally situated out of the path of movement of said projection, and means to move the dog into such path of movement when a defect is formed in the product, 115 whereby the projection on the shaft engages the dog and thus shifts the knock-off lever to release the latch.
2. In a braiding machine, the combination with braiding mechanism, of a driving shaft 120

- 130

therefor having a projection 35, a knock-off lever 18 controlling the operation of the shaft, a dog 33 carried by the knock-off lever and normally situated out of the path of

5 movement of the projection, a gauging eye through which the braided product passes from the braiding point, and connections between said eye and dog by which the latter

is shifted into the path of movement of the projection when said eye is moved by a knot, 10 bunch or other enlarged portion of the braided product.

In testimony whereof, I have signed my name to this specification.

FRANK W. MANSFIELD.
